UNITED STATES PATENT OFFICE.

CLARENCE D. PETERS, OF ETHERLEY, ILLINOIS.

RAIL-JOINT.

No. 809,217.

Specification of Letters Patent.

Patented Jan. 2, 1906.

Application filed July 14, 1905. Serial No. 269,681.

To all whom it may concern:

Be it known that I, CLARENCE D. PETERS, a citizen of the United States, residing at Etherley, in the county of Knox and State of Illinois, have invented new and useful Improvements in Rail-Joints, of which the following is a specification.

The invention relates to an improvement in rail-joints designed to support the rail to prevent sagging and to secure the meeting ends together to prevent independent longitudinal movement.

The main object of the present invention is the production of auxiliary means designed for coöperation with the specially-formed meeting ends of rails and adapted when in operative position to prevent independent movement of the rails in any direction.

The preferred details of structure will be described in the following specification, reference being had particularly to the accompanying drawings, in which—

Figure 1 is a perspective view illustrating my improved rail-joint. Fig. 2 is a horizontal section thereof, taken immediately below the tread of the rail. Fig. 3 is a vertical section through the same, the wedges being shown in elevation. Fig. 4 is a transverse section showing the wedges locked in operative positive.

Referring to the drawings, it will be noted that the ends of the rails designed to coöperate with my improved auxiliary securing means are enlarged to provide for the reception of the operating mechanism, the base of the rail 1 being widened, as at 2, to provide an increased bearing-surface and the web of the rail being thickened at 3, said thickened portion being hollow or recessed to provide a housing 4, having vertically-arranged side walls, as shown. The meeting ends of the rails proper—that is, the tread portions, web portions, and base-flanges—are cut in reverse directions on a line diagonal to the longitudinal dimension of the rail to prevent lateral movement of the rail ends when secured together.

The walls of the housing 4 of one of the rail ends are each provided with a longitudinally-arranged slot 5, these slots being in parallel alinement to provide for the operation described. Wedge-blocks 6 and 7 are adapted for insertion within the housing, the lower face of the wedge 6 being formed on an upward incline and the upper face of the wedge 7 being similarly formed, whereby the meet-

ing faces of these wedge-blocks are adapted for action, the remaining faces of these wedge-blocks being of a contour to correspond with that of the housing, whereby said blocks are slidably mounted within the housing and readily moved from one position to the other, being guided by the housing-walls. Near the rear end each of the blocks is formed on the inclined face with a transversely-arranged semicircular depression 8, designed when in register with each other to provide a circular opening extending transverse the blocks, as illustrated in dotted lines in Fig. 3. The respective vertical dimensions of the blocks is such that when the blocks are within the housing formed with the longitudinally-arranged slots 5 said recesses 8 are in alinement and register with the slots 5 near their rear ends. The inclined faces of the wedge-blocks are also provided with semicircular depressions 9, which when in register with each other form transverse bolt-receiving openings. The depressions 9 are so formed, however, that when the depressions 8 are in register the depressions 9 will be out of register, as shown in dotted lines in Fig. 3.

The wedge-blocks are of a length to seat completely within that rail formed with the longitudinally-arranged slots 5, whereby the rails may be assembled in proper position without interference with the wedge-blocks. It is further understood that the depressions 9 are so arranged in the wedge-blocks that when the parts are in locking position the respective depressions 9 will be in transverse alinement with bolt-holes 10, formed in the side walls of the respective housings of both rails.

In use the rail ends of my improved rail-joint are arranged in alinement, so that the respective housings register longitudinally, it being understood that in the initial positions of the parts the wedge-blocks 6 and 7 are wholly within the housing formed with the longitudinal slots and bearing against the rear wall of said housing, so as to register the depressions 8 in the respective blocks, and thereby form an opening transverse of the wedge-block and in communication with the slots 5 near their rear ends. To lock the rails together, a suitable tool, as a punch, is inserted in the opening formed by the registering depressions 8, and the wedge-blocks as a whole are moved into the housing of the adjacent rail end. As the depressions 9 do not register when the depressions 8 are in register, this

movement of the wedge-blocks, while probably alining the depressions 9 of the wedge-block 7 with the bolt-openings 10, will not aline the depressions 9 of the wedge-block 6 there-
 5 with. To secure this necessary alinement, the upper wedge-block 6 is driven by a suitable tool, preferably by its insertion in one of the exposed recesses 8, a slight distance forward to aline the depressions 9 with the
 10 depressions 9 in the lower block, this forward movement of the upper block serving also to tightly wedge the blocks in place, as will be apparent. A suitable tool, as a punch, is now inserted through one of the bolt-holes
 15 10 and driven transversely of the wedge-blocks to insure the absolute alinement of the depressions 9 with each other and with the bolt-holes, after which the usual bolts 11 are inserted therethrough and secured beyond the
 20 walls of the housing in the usual manner.

It is to be understood that the slots 5 are of a length to permit the described operation of the wedge-blocks, whereby to provide for the convenient locking or unlocking of the parts.

25 As the wedge-blocks are not in coöperative wedge action until the final movement of the upper block, it is evident that the wedge-blocks are readily moved longitudinally of the housing in their initial operation, and that
 30 therefore the securing of the locking means in place is readily and conveniently accomplished.

The securing-bolts 11 by their coöperation with the respective depressions in the wedge-blocks tend to maintain said blocks in their wedge coöperation with each other and with the housings. The lock is a secure one, and the rail ends are maintained in perfect alinement and prevented from movement in any
 35 40 direction.

Having thus described the invention, what is claimed as new is—

1. In combination with the meeting ends of railway-rails, of wedge-blocks designed to be
 45 moved longitudinally of the rails without wedging action, means to move one of said blocks with relation to the other to produce a wedging action, and means to hold said blocks in wedging position.

50 2. In combination with the meeting ends of railroad-rails, of wedging-blocks designed to

coöperate therewith and movable longitudinally of the rails, said blocks being formed with means arranged to register to permit their longitudinal movement, means arranged to register when said blocks are in wedging position, and means to coöperate with said last-mentioned means to lock the blocks in wedging position.

3. The combination with railroad - rails formed with registering housings at their meeting ends, wedge-blocks longitudinally movable in said housings, two sets of depressions formed in each wedge-block, the depressions of one set being in register in the respective blocks only when the blocks are in wedging position, and means to engage said registering depressions.

4. The combination with railroad - rails formed with housings adapted to longitudinally aline when the rails are in position, wedge-blocks seated in one housing and adapted to coöperate with the other, each of said wedge-blocks being formed with an operating depression adapted to aline with each other for the initial movement of the blocks, each of the blocks being formed with locking depressions normally out of register, said locking depressions registering only after the wedging action of the blocks, and means engaging the walls of the housing and said registering locking depressions.

5. The combination with railroad - rails formed with longitudinally-arranged housings at their meeting ends, of wedge-blocks normally within one housing and adapted to coöperate with the other, each of said wedge-blocks being formed with operating depressions and with locking depressions, said locking depressions being out of register in the respective blocks when the operating depressions thereof register, the walls of the housing being formed with longitudinally-arranged slots adapted to register with the operating depressions in the wedge-blocks.

In testimony whereof I affix my signature in presence of two witnesses.

CLARENCE D. PETERS.
